Atty.

UNITED STATES PATENT OFFICE.

WILLIAM M. MITCHELL, OF LOUISVILLE, KENTUCKY.

ANTICREEPING DEVICE FOR RAILROAD-RAILS.

1,235,496.

Specification of Letters Patent. Patented July 31, 1917.

Original application filed March 31, 1917, Serial No. 158,791. Divided and this application filed June 5, 1917. Serial No. 173,041.

To all whom it may concern:

Be it known that I, WILLIAM M. MITCHELL, a citizen of the United States, and resident of Louisville, county of Jefferson, and State 5 of Kentucky, have invented certain new and useful Improvements in Anticreeping Devices for Railroad-Rails, of which the following is a specification.

The present application is a division of 10 an earlier application, filed by me, March 31, 1917, Serial No. 158,791.

The invention relates to anti-creeping devices for holding railway rails against longitudinal movement, and seeks to provide a 15 simple, effective construction which is securely fixed to the rail, and which preferably also acts as a tie plate. The invention consists in the features of improvement hereinafter set forth, illustrated in the preferred forms in the accompanying drawings, and more particularly pointed out in the appended claims.

In the drawing:—

Figure 1 is a plan view of one form of 25 the present invention;

Fig. 2 is a cross section on the line 2—2 of Fig. 1;

Fig. 3 is a plan view of another form; and

Fig. 4 is an end view, parts of the rail being shown in section on the line 4—4 of 30 Fig. 3.

The form shown in Figs. 1 and 2 comprises a plate 1 inserted between the tie 2 and the base of the rail 3. The plate is provided, on its lower face, with depending 35 tie indenting portions 4, and, upon its upper face, with raised parts 5 upon which the base of the rail rests. The plate is also provided with a shoulder or longitudinal rib 6 which extends along one edge of the rail base, and the plate is provided with openings for receiving spikes 7 which are driven therethrough into the tie, and the heads of 40 which overlap the edge portions of the rail base.

The plate or anti-creeping device is held 45 against movement by the engagement of the spikes with the tie and it is solidly and permanently united to the rail base by welding or fusing the opposite edges of the latter to the adjacent portions of the plate. Preferably a fillet is fused from a steel rod by means of a suitable oxy-acetylene torch and

run into the space between the shoulder 6 55 and the adjacent edge of the rail base, while the latter are heated by the torch nearly to the fusion point. Such a fillet is indicated at *a* in Fig. 2, and the metal body thereof is integrally united to the adjacent portion of 60 the shoulder and the rail base. In a similar manner, a fillet *b* unites the opposite edge of the rail base to the adjacent portion of the plate.

In the preferred form shown in Figs. 3 65 and 4, the tie plate 8 is provided at diagonally opposite corners with upwardly and inwardly projecting lugs 9, and at the other diagonally opposite corners, the plate is provided with holes for receiving retaining 70 spikes 10. The lugs 9, together with the body of the plate, form jaws which are arranged to embrace the opposite base flanges of the rail, the space between the jaw lugs 9 being sufficient to receive the base flange 75 between them, and then permit the engagement of the jaw lugs with the upper face of the base flange by twisting the plate in a horizontal direction.

The opposite edges of the rail base are 80 welded or fused to the adjacent portions of the plate and the inner ends of the hooks or jaw lugs 9, which overlap the base flanges, are welded to the upper faces of the base flanges of the rail. Preferably fillets *c* are 85 fused to the connected parts and extend along the edges of the rail base and along the ends of the hooks or jaw lugs, as shown. Preferably also, these fillets, at diagonally opposite corners of the plate adjacent the 90 spikes, are enlarged into bosses *d*, which extend upwardly and inwardly over the base flanges of the rail. The improved anchor or anti-creeping device is thus securely united to the rail base without weakening 95 the metal body thereof and effectively cooperates with the tie to prevent creeping. In the preferred form shown, it also acts as a tie plate.

It is obvious that changes may be made in 100 the details set forth without departure from the essentials of the invention as defined in the claims.

I claim as my invention:—

1. In anti-creepers for railway rails, the 105 combination with a rail and its supporting cross tie, of a plate interposed between the tie and the rail base and spiked to the tie.

and metal fillets fused or welded to the opposite edges of the rail base and to adjacent portions of said plate.

2. The combination with a rail and its supporting cross tie, of an anchor comprising a plate interposed between the tie and the base of the rail and spiked to the tie, said plate having jaw lugs overlapping and welded to the opposite base flanges of the rail.

3. In anti-creeping devices for railway

rails, the combination with a rail and its supporting cross tie, of a plate interposed between the tie and the rail base and spiked to the tie, and metal fillets fused or welded to the opposite edges of the rail base and to adjacent portions of said plate, said fillets being extended upwardly over and welded to the upper faces of the base flanges of the rail.

In testimony whereof I affix my signature. 20

WILLIAM M. MITCHELL.

Copies of this patent may be obtained for five cents each, by addressing the "Commissioner of Patents, Washington, D. C."
